UNITED STATES PATENT OFFICE.

WALTER L. STADIG, OF SOLDIER POND, MAINE.

SNOW-PLOW.

1,084,498.

Specification of Letters Patent.

Patented Jan. 13, 1914.

Application filed August 18, 1911, Serial No. 644,833. Renewed April 25, 1913. Serial No. 763,653.

To all whom it may concern:

Be it known that I, WALTER L. STADIG, a citizen of the United States, and a resident of Soldier Pond, in the county of Aroostook and State of Maine, have invented a new and Improved Snow-Plow, of which the following is a full, clear, and exact description.

The invention relates to plows for clearing snow from road-ways, and an object of 10 the invention is to provide a machine so mounted on sleds as to accommodate itself to uneven roads; to provide for convenient adjustment of the snow removing devices to the end that a wider or narrower way may 15 be cleared as may be desired, and the snow removed to produce an essentially level way, or to leave a ridge or comb at the center.

Other objects and advantages of my improved machine will appear, from a more 20 particular description hereinafter to be given.

Reference is to be had to the accompanying drawings, constituting a part of this specification, in which similar characters of 25 reference denote corresponding parts in all the views and in which

Figure 1 is a side elevation of a snow plow embodying my invention; Fig. 2 is a plan view thereof; Fig. 3 is a rear elevation with 30 parts in section on approximately the line 3—3 Fig. 2, and with other parts removed; Fig. 4 is a side elevation of the spiral conveyer for elevating the snow, the housing of the conveyer being in section; Fig. 5 is a 35 similar fragmentary view taken at right angles to Fig. 4; Fig. 6 is a detail perspective view of one form of cutter that may advantageously be employed; Fig. 7 is an enlarged detail vertical section of one of the 40 wheels and its appurtenances for raising or lowering the snow removing devices; Fig. 8 is a detail view in front elevation of the 45 rear sled with parts in section on the line 8—8 Fig. 1; Fig. 9 is an inverted plan view of the swivel seat which is shiftable for the operator to readily turn either of the adjusting wheels; Fig. 10 is a perspective view of the spreader or plow proper; and Fig. 11 is a front elevation of the frame showing the 50 spindles on which the cutters are mounted adjusted to a greater width than indicated in the arrangement illustrated in the other figures.

The snow removing devices comprise essentially a spreader or plow proper composed in the main of diverging sides or

wings, the spreader traveling at the approximate center of the machine, and the rear ends of the wings serving to deliver and feed the snow to cutters, one of which is adjacent to each terminal of the wings of the spreader, the said cutters in turn forming a feed and delivering the snow to a conveyer, the conveyer advantageously, as in the present instance, being in the form of a spiral 65 or screw elevator arranged vertically.

Any suitable motor, such as an internal combustion engine is mounted on the frame, and driving connections are made with the arbors or shafts of the cutters and with the 70 screw conveyers that elevate the snow.

In constructing a snow plow in accordance with my invention, a suitable frame work is provided which may consist as shown of longitudinal beams 10 suitably 75 braced by cross bars 11 and bolts 12 or other strengthening means, the frame being mounted on front and rear sleds 13—14. The front sled has its knee 15 preferably connected with cross beams 16 by a ball and 80 socket joint 17 so as to respond to the unevenness of the road and to the movement of the draft animal. The rear sled, as shown best in Fig. 8, has hinged connection to permit of forward and backward rocking movement, the said hinged connection being conveniently established by providing disk-like hinge members 18 on the knees 19 of the sled 14, and similar hinge members 20 depending from a cross beam or bolster 21 secured to the longitudinal beams 10. Members 22 may be employed in connection with the cross beam 21, and the support of the ball of the front sled joint may be secured by arms 24. The snow removing members 85

are mounted about centrally of the machine on a vertical frame 25, on which frame and advantageously at the outer sides thereof, the arbors or shafts 26 of the cutters 27 are mounted in suitable bearings 28—29, said 90 bearings being supported on transverse rods 28 and 29^a or their equivalents. The rods 28^a and 29^a are supported from the frame members 25 in any suitable manner. The spreader 30 is supported centrally of the 105 machine in front of the cutters 27. In the present instance the said spreader is suspended at its apex from an eye-bolt 31 which passes through a transverse hanger beam 32 which is connected near its ends to hanger 110 rods 33, the rear ends of which are connected respectively with sleeves 34 formed

on a rack 35 hereinafter to be described as one of the elements for lifting the spreader, the cutters and the conveyers. The rear ends of the two diverging wings composing the main body of the spreader 30 are connected with the forward ends of arms 36 that emanate from divided collars 37 secured on each arbor 26 at a point above the cutters 27. The arms 36 and collars 37 hold the wings against collapse, and the wings may be spread or contracted by adjusting the shafts 26 toward or from each other. The housings or casings 38 surrounding and carrying the spiral conveyers 39 are also supported from the shafts 26 being connected thereto by arms 40 near the top, each arm 40 being forked as at 41 or given a semi-circular form as at 41, and bolted as at 42 to the housing 38. Similarly arms 43 extend rearwardly from the collar 37 and extend in the form of a semi-circular fork 44 which is also bolted to the casing 38. Said casing is provided at its lower end with a boot or horizontal receiver 45, to and through which the cutters 37 deliver the snow, and at the upper portion the said housing is provided with any suitable chute or outlet 46 through which the snow is discharged toward the side of the road.

30 In the example shown, the spreader wings are each provided with a horizontal cutting blade 47 having transverse cutting edge 48 and desirably also with an auxiliary vertical cutting member or blade 49, the cutters 48 being suitably secured to the wings as for instance by means of the flanges 50 bolted to the inside of each wing 30. Between the spreader wings 30 and connected therewith, toggle arms 51 are secured at their forward ends to the respective wings 30 and connected to each other at 52; similarly at any desired point below the adjusting devices 51 there are secured to the inside of the wings 30 hinge members 53 united to each other as at 54^a. The elements 51-53 serve as braces. The cutters may be in the form of two or more spiral blades, two being shown in the present instance as in Fig. 6. Advantageously the actuating means for the cutters, cutter shafts and the conveyers may be as follows: On the shaft 54 of each conveyer 39 is a sprocket wheel 55, and the sprocket chain 56 extends around said wheel and a sprocket wheel 57 on each arbor 26 for driving the spiral conveyer. The arbors are provided with suitable driving connections from any approved form of motor 58. The adjustment of the wings, to spread or contract the same, is accomplished manually in the illustrated example.

60 In the illustrated construction, there is a driving shaft 59 mounted in bearings 60 at the top of the frame 25, said shaft being actuated from the motor by suitable connections such as sprocket wheels 61-62 and

chain 63 and driving connection between the shaft 59 and the arbors 26 is effected by means of beveled pinions 64, 65 on the said shaft and arbors respectively. The mentioned racks 35 are suitably held one on each arbor 26 as by set collars 66, and meshing with said racks are the spur pinions 67 on a transverse shaft 68 which is provided also with beveled pinions 69 that mesh with similar pinions 70 on longitudinal shafts 71 that extend forwardly to the head frame 72, said shafts 71 being provided with beveled pinions 73 meshing with similar pinions 74 on the spindles 75 of hand wheels 76, so that by the driver turning the wheels 76, the racks 35 will be raised, thereby raising the cutters 27 and through the described connections raising also simultaneously with the cutters, the spreader 30 and the spiral conveyers 39 with their housings 38. Thus the described snow removing members may be raised and lowered as desired. When it is desired to leave a ridge or comb in the road-way, instead of clearing the snow substantially to the road level, the spreader arms 36 may be sustained in a more elevated position by adjusting the bolt 31 in the hanger beam 32 and securing the arms 36 at the upper series of bolt holes 36^a.

35 In order that the driver's seat 77 may readily swivel to enable the driver to turn toward either one of the hand wheels 76, the said seat is provided and mounted to conveniently turn on a spindle 78. The seat support 81 is provided with arcuate slots 100 through which studs 80 project from the seat.

40 Each hand wheel 76 is provided with suitable means for holding it in any given position to maintain the snow cutters, etc., in the adjusted position. I have shown the wheel provided with a pin 82 movable vertically in a housing 83 and provided with a head or grip 84. A spring 85 normally tends to press the pin into engagement with any one of an annular series of recesses 86 in any suitable portion in the frame work below the wheel.

45 In Fig. 3 it will be seen that the shaft 59 is divided, the ends being coupled by flanges 87 or other suitable means. Similarly, the transverse rods 28^a and 29^a are divided, and the divided ends secured by flanges 88-89. All the mentioned flanges are bolted together.

50 In Fig. 11 I have shown the arbors 26 adjusted to a greater distance from the sides of the frame to correspond with a widening of the plow proper or spreader 30. The wider adjustment of the arbors 26 is effected in the present instance by interposing a section 90 in the shaft 59 as clearly shown in Fig. 11. Similarly sections 91 and 92 are interposed in the rods 28^a and 29^a. On the runners of both the forward and the rear

sleds, sharpened plates 93 are secured to prevent side movement of the sleds.

Having thus described my invention, I claim as new and desire to secure by Letters Patent:

1. In a snow plow, the combination of independent front and rear sleds, a motor mounted above the rear sled, snow removing means between the sleds, said means including a cutter, driving connections between the motor and the cutter, and elevating means for the removing means, said elevating means being operable from a point above the front sled.

15 2. In a snow plow, the combination of spaced rotary cutters, a plow in advance of the cutters and having diverging wings leading to the cutters, and elevating conveyer screws fed by the cutters, the said conveyer screws having housings provided with discharge chutes.

25 3. The combination with front and rear sleds, of a cutter between said sleds, a revolving vertical shaft carrying said cutter and mounted for vertical movement, a snow-gatherer delivering to said cutter and having support from members loose on said shaft, a rack loose on the shaft, but movable vertically therewith, a pinion in mesh with said rack, and means for turning said pinion from a point above the front sled for raising and lowering the rack and with it the shaft, its supported cutter and snow gatherer.

35 4. In a snow plow having front and rear sleds and snow-removing means mounted on a shaft between said sleds; the herein-described means for raising and lowering said shaft, comprising a rack on the shaft, a pinion in mesh with the rack, a forwardly extending shaft, and a vertical spindle geared to the forwardly extending shaft and provided with a hand wheel, said wheel having means for holding it in a given position to maintain the snow remover in adjusted position.

45 5. In a snow plow, the combination of snow gathering means at each side of the plow, the means at each side being mounted on a vertical member carrying a rack, a transverse shaft having pinions in mesh with said rack, forwardly extending shafts having pinions in mesh with the first mentioned shaft, vertical spindles geared to the said forwardly extending shaft, hand wheels on said spindles, and a driver's seat located between the said wheels.

60 6. In a snow plow, the combination of snow gathering means at each side of the plow, the means at each side being mounted on a vertical member carrying a rack, a transverse shaft having pinions in mesh with

said rack, forwardly extending shafts having pinions in mesh with the first mentioned shaft, vertical spindles geared to the said forwardly extending shaft, hand wheels on 65 said spindles, and a driver's seat located between the said wheels, said seat being swiveled to turn toward either of the wheels.

7. In a snow plow, the combination with front and rear sleds and an elevated frame 70 supported from the sleds, of suspended rotary cutters carried by the frame between the sleds and at the outer sides of said frame, and a suspended plow beneath the frame and comprising diverging wings extending at 75 their rear ends outward beyond the sides of the frame at points to deliver snow to the said cutters.

8. In a snow plow, the combination with front and rear sleds and an overhead frame 80 supported from the sleds, of snow-gathering means comprising suspended rotary cutters carried by the frame intermediate the ends thereof and outside of the frame, and snow-gathering means mounted within the frame 85 and having wings extending beyond the sides of the frame to points in line with the cutters.

9. In a snow plow, the combination of a frame, front and rear sleds on the said frame 90 and snow-removing means between said sleds and supported from the said frame, below the frame, the said means consisting of a snow-gathering device rearward of the front sled, an elevating snow conveyer having a 95 horizontal receiving boot at the foot thereof, and a rotary cutting means between the snow-gathering device and the conveyer, the said cutting means being mounted on a vertical axis suspended from the frame and serving to deliver the snow to the boot of the conveyer.

10. In a snow plow, the combination with a frame of a rotary cutter, a vertical arbor on which said cutter is mounted below the 105 frame, a snow-gatherer in the form of deflecting wings arranged to travel beneath the frame in front of the cutter and serving to deliver snow to said cutter, conveying means mounted in line with and behind said cutter 110 and arranged to receive the snow from said cutter, means connecting the cutter, the gatherer and the conveyer, and means for raising all in unison, toward and from the frame.

In testimony whereof I have signed my 115 name to this specification in the presence of two subscribing witnesses.

WALTER L. STADIG.
